UNITED STATES PATENT OFFICE.

JACOB LIVINGSTON HILL, OF PHILADELPHIA, PENNSYLVANIA, ASSIGNOR, BY DIRECT
AND MESNE ASSIGNMENTS, TO SLIP SCARF COMPANY, A CORPORATION OF NEW
YORK,
NECKTIE.

1,005,835.

Specification of Letters Patent. Patented Oct. 17, 1911.

Application filed June 10, 1908. Serial No. 437,678.

To all whom it may concern:

Be it known that I, JACOB LIVINGSTON HILL, a citizen of the United States, residing at Philadelphia, county of Philadelphia, and State of Pennsylvania, have invented a new and useful Improvement in Neckties, of which the following is a full, clear, and exact description, reference being had to the accompanying drawings, which

10 form a part of this specification.

The object of my invention is to so modify the structure of a necktie that, when used with the generally worn turn-down linen collar, it may be readily pulled back 15 and forth, in the operation of forming a knot, thereby facilitating the operation and avoiding undue strain upon the tie.

As is well known, the ordinary four-inch hand tie (to which the invention is particularly applicable, although not limited thereto) comprises an elongated two-ply strip of fabric having cotton wadding or filling between the plies. The central part of the tie is placed between the outer and inner 25 folds of the collar, preparatory to securing the collar to the shirt. The bow or knot is then formed. In the formation of the bow or knot, it is necessary, to make a neat effect in tying, to pull one or the other or 30 both ends of the tie, requiring that the central section of the tie shall slip back and forth between the two folds of the collar. It is always difficult, and sometimes impossible, to do this without pulling or dragging 35 the tie with considerable force, causing injury to the tie, collar, or shirt. The tie may be torn, the padding or filling may be pulled out of place, the collar may be distorted or a button-hole in the neck-band of 40 the shirt or collar may be torn out. At best, the difficulty in sliding the tie to just the proper position is so great that the final effect is more or less unsatisfactory.

I have discovered that the resistance of 45 the tie to free sliding movement is due primarily to the thickness and clinging nature of the tie; the thickness of the tie causing it to be confined with considerable pressure between the folds of the collar when the 50 ends of the latter are buttoned to the front of the neck-band, while the softness and clinging nature of the tie, to some extent, causes a resistance to free movement in a circular direction after the collar is in po-

sition. To remedy these defects in a practicable way, it is necessary to avoid any complications of structure that would give rise to new evils of a more serious nature than those which it is sought to remove; and it is also desirable to avoid any substantial departure from the external appearance and unitary character of the present form of tie to which the public has been educated.

I have discovered that the defects enumerated may be entirely eradicated by various expedients having certain features in common, the description of which will be best understood by making reference to the accompanying drawings in which—

Figure 1 is a perspective view of a tie embodying my invention, the intermediate part being shown on edge. Fig. 2 is another perspective view of the same showing a face view of the intermediate section. Fig. 3 is a perspective view of the same in position on the collar which is partly broken away; Figs. 4 and 5 are enlarged sections on the lines 4—4 and 5—5 respectively of Fig. 1, the thickness of the material, and especially of the cover, being exaggerated for purposes of clearness; Fig. 6 is a plan view, on a reduced scale, of a filling strip embodying my invention and ready for application to the tie; Fig. 7 is a longitudinal section, greatly enlarged, at the junction of the intermediate part and one end part of the filling of Fig. 6. Fig. 8 is a plan view, similar to Fig. 6, showing the filling made of a single piece.

I will first describe the preferred embodiment of my invention.

I first prepare (see Fig. 6) a strip *a* of muslin or other relatively thin material corresponding in length and width to that intermediate part of an ordinary filling piece for neck ties that in use is confined between the folds or wings of the collar. I apply to this strip sizing or stiffening material. Various sizing compositions may be used, such, for instance, as gelatin, starch, gum arabic, glue or a mixture of glue and glycerin. To the ends of the sized strip I then attach, preferably by sewing, end strips *b*, *b*, of cotton wadding, or other relatively soft and thick material; these end strips forming, in connection with the intermediate strip, a filling piece corresponding in length

and breadth to the ordinary filling piece, composed entirely of cotton wadding, that is commonly in use as a filling piece for neckties. This compound filling piece, prepared as described, is then inserted between, and confined within, the two plies of the cover *c* of a tie, in the ordinary manner. That part of the tie including the sized intermediate strip is then subjected to heat and pressure which causes the sizing material with which the strip *a* is impregnated to more or less dissolve and penetrate the covering material overlying it and imparts to the intermediate portion of the tie a smooth surface. The result is that the finished tie is provided with an intermediate section, adapted to be placed between the folds of a collar, so thin that it will not be tightly confined therein, and so smooth that it will slide freely after the collar is secured to the shirt.

After the filling piece is inserted within the tie cover as above described, it may be advisable to form two lines of plain or fancy stitches *d* transversely of the tie at the junction between the intermediate part and each end part of the tie, these stitches extending through cover *c* and the overlapping parts of strips *a* and *b*. This effectually prevents any displacement of the filling during the pressing operation or during subsequent use.

The desired steaming and compressing actions may be effected by placing a wet cloth over the intermediate part of the tie and then ironing with an ordinary flat iron or passing this part of the tie between pressure rollers or by compressing the same between heated plates. If the tie as a whole is pressed and finished by means of heat and pressure, it will be unnecessary to subject the intermediate part to any special treatment, as the temporary softening of the sizing substance, its penetration from the inside into the tie cover, and the final smoothing and compressing of the same will be effected incidentally.

The relatively thin and smooth intermediate part of the tie should preferably not extend entirely around the neck when the tie is placed in the collar, but should terminate short of the ends of the collar so as to allow considerable leeway in tying.

While I have spoken of the strip *a* as an intermediate part, it will be understood that ordinarily this section, in an ordinary four-in-hand tie, will be closer to one end of the filling piece than the other, one of the end strips *b* being made longer than the other to allow it to be folded around the other in the ordinary manner of forming the ornamental loop. It will be understood that this central strip will usually be substantially narrower than the end strips, but only to the extent that the intermediate portion

of an ordinary filling piece or necktie is narrower than the end portions, it being intended to have the longitudinal edges of the strip *a* in alinement with the longitudinal edges of the strips *b*, *b*.

One of the valuable features of my invention is that a tie embodying the same does not differ noticeably in appearance from the ordinary tie even when it is not in use, while it presents the same appearance when worn as the ordinary tie.

While it is preferred to make the intermediate part *a* of the filling piece of different and thinner material than the end parts *b*, *b*, this is not absolutely essential; as the invention may also be carried out by making the part *a* of the same material, preferably cotton or wadding, as the parts *b*, *b*, and in one unitary strip as shown in Fig. 8. The sizing of the part *a* thereof, followed by heating and compressing the intermediate part of the tie, will effect the desired result of making this part of the tie substantially thinner and smoother than the end sections of the tie.

The invention may also be carried out by taking the filling piece of either Figs. 6 or 8, but without applying sizing to the section *a*, and inserting and confining the same within the cover of a tie, then applying sizing material to the outside of the intermediate section of the tie, and then applying heat and pressure as above described.

The invention may also be carried out by altogether omitting the intermediate part *a* of the filling piece and preferably, in addition applying sizing to the intermediate part of the tie, preferably to the inside thereof, before the same is sewed into shape.

The invention may also be carried out by taking a thin sheet of solid gelatin or glue, or other suitable sizing and substituting it for, or applying it to, the intermediate part of the filling. Less preferably, the tie may be formed by utilizing a filling piece similar to that shown in Fig. 6 in which the sizing may be omitted from the strip *a* or from that part of the tie inclosing the strip, reliance being had wholly upon the greater natural thinness, or stiffness and thinness, of the strip *a* to impart to the tie the desired capacity of ready slippage between the wings of the collar.

In ties composed of such thickness that a filling piece is omitted, the desired result may be produced by sizing, and then heating and pressing, the intermediate section thereof, as before described.

I do not herein claim as my invention the specific embodiment of my broad invention wherein the neck-band section of the cover, or a portion thereof, is made of anti-friction material different from the material of which the remaining part of the cover is made.

Having now fully described my invention, what I claim and desire to protect by Letters Patent is:

1. A necktie formed of an elongated two-ply fabric and a filling piece confined between the plies in which both the two-ply fabric and the filling piece extend substantially throughout the length of the tie, and comprising relatively thick and soft end sections and a relatively thin and smooth intermediate section. 5
  2. A necktie formed of a two-ply covering fabric extending continuously throughout the length of the tie and a filling piece confined between the plies, in which an intermediate portion of the tie is substantially thinner and smoother than the end portions. 10
  3. A necktie comprising an elongated fabric having a central section of substantially greater smoothness and less thickness than the end sections and in which the ends of the intermediate section are of substantially the same width as the adjacent ends of the end sections and in which the edges of adjoining sections are substantially flush or in alinement. 15
  4. A necktie comprising a cover and filling in which the cover extends continuously throughout the length of the tie and in which an intermediate portion of the tie is substantially thinner than the end portions. 20
  5. A necktie, formed of an elongated two-ply fabric and a filling piece confined between the plies, in which both the two-ply fabric and the filling piece extend substantially throughout the length of the tie, said tie having a sized and compressed intermediate section whereby the tie is rendered freely slideable between the folds of a collar. 25
  6. A necktie comprising two end sections and a sized and compressed intermediate section in which the longitudinal edges of the intermediate section are substantially flush or in alinement with the longitudinal edges of the end sections. 30
  7. A necktie formed throughout its length of an elongated two-ply cover fabric and a filling piece, confined between the plies, comprising an intermediate filling strip of sized and relatively thin material and unsized end filling strips of relatively thick material. 35
  8. A necktie formed throughout its length of an elongated two-ply cover fabric and a filling piece, confined between the plies, comprising an intermediate filling strip of relatively thin material and end filling strips of relatively thick material whose longitudinal edges are substantially flush or in alinement with the longitudinal edges of the intermediate strip. 40
  9. A filling piece for neckties having a sized intermediate portion and unsized end portions. 45
  10. A filling piece for neckties comprising end filling strips of relatively thick and soft material and an intermediate filling strip of relatively thin material whose longitudinal edges are substantially flush or in alinement with the longitudinal edges of the end strip. 50
  11. In a necktie the combination of a neckband and two tying ends, an interlining in said necktie thinner in the neckband portion than in the tying ends. 55
  12. As an article of manufacture, a necktie having two tying ends and a neckband made of suitable fabric, a portion of said neckband being thinner but of substantially equal width with the adjoining portion of said neckband. 60
  13. As an article of manufacture, a necktie having two tying ends and a neckband made of suitable fabric, a portion of said neckband being thinner but of substantially equal width with the adjoining portion of the neckband, and interlinings in the tying ends independent of each other. 65
  14. As an article of manufacture, a necktie having two tying ends and a neckband made of suitable fabric, a portion of said neckband being substantially solid and thinner than the adjoining portions and of substantially equal width with the adjoining portions. 70
  15. A necktie formed of an elongated two-ply fabric and a filling piece confined between the plies, said filling piece being thinner in a portion of the neckband than in the tying ends, and being secured between the plies of the said fabric by means of rows of stitching. 75
  16. A necktie comprising two end sections and a compressed intermediate section containing a sized interlining. 80
- In testimony of which invention, I have hereunto set my hand, at Philadelphia, on this 6th day of June, 1908.
